PIPE CLEANER
Sumas Payne, 8522 S. Maryland,
Chicago, Ill. 60619
Filed Aug. 27, 1964, Ser. No. 392,447
1 Claim. (Cl. 131—246)

This invention relates broadly to smokers' accessories and, more specifically, to appliances which are designed to clear away accumulated obstructions of any kind and to loosen and remove any deposits in the bowl to a tobacco pipe.

The principal object of the present invention is to provide novel and improved accessories of the aforementioned comprising parts of special construction and operation.

A second object of the invention is to provide a smoker's article of the type aforementioned which is composed of two parts which will, when assembled, provide a tool for reaming out the layer of hard ash that forms on the inside of a smoking pipe bowl.

A third object of the invention is to provide a reamer having novel helical tooth cutters on the convex outer surface thereof, the latter of which is adapted to scrap the cake from the inside of a pipe bowl when rotated therein.

Further objects of the invention of the class described are to provide a combination pipe bowl and pipe stem cleaner set that is extremely inexpensive, easy to use, versatile, pleasing in appearance, simple to manufacture, and a set that is adaptable for use in many different sizes, types and styles of pipe bowls.

Other objects will be in part apparent and in part pointed out specifically hereinafter in connection with the description of the drawing that follows, in which:

FIGURE 1 is a side elevation showing the pipe cleaner of the present invention positioned within a pipe bowl cutting the ash therefrom, the pipe being shown in section;

FIGURE 2 is an end view of the handle portion of the pipe cleaner shown in FIG. 1;

FIGURE 3 is a side elevation of the pipe cleaner shown in FIG. 1, with a portion of the convex-cutter shown in section;

FIGURE 4 is an end view of the handle portion of the pipe cleaner, with the convex-cutter removed, and showing the tapered tenon thereof;

FIGURE 5 is a front end view of the pipe reamer, showing the end portion of the convex-cutter with the coarse helical teeth;

FIGURE 6 is a rear end view of the convex-cutter of the reamer, showing the truncated conical socket thereof;

FIGURE 7 is a side elevation showing the liquid absorber tool, with the rubber head in cross-section, with the adjacent portion of the handle in section, the rubber head shaped as a segment of paraboloid of revolution;

FIGURE 8 is a rear end view of the liquid absorber tool rubber head, showing the tapered tenon thereof;

FIGURE 9 is a vertical section taken on line 9—9 of FIG. 7;

FIGURE 10 is a rear end view of the liquid absorber tool;

FIGURE 11 is a side view of the pipe-stem cleaning tool constructed in accordance with an embodiment of this invention; and

FIGURE 12 is a side view of a pipe cleaner adapted to be inserted into the bore of the shank adjacent the bowl of the pipe, after the stem of the pipe has been removed from the pipe shank during cleaning thereof.

2

Referring now to the drawing for a detailed description of the invention, and in particular to FIGURES 1-6 thereof, it will be seen that the pipe cleaner, which has been identified broadly by numeral 15, consists of a body, or wooden handle 16, or other suitable material can be used, and a metal reamer 17 assembled together. The handle 16 has a rounded free end portion 18 at one end, and at its opposite end is provided with a disc portion 19 of maximum diameter substantially the same as the transverse diameter of the handle, a disc or step-portion 20 of smaller diameter than said disc portion 19, and a tenon 21 carried by and spaced axially from the body 16 by said disc portion 19 and step portion or disc 20, said tenon being a truncated conical head member 15 integrally formed with said discs 19, 20 and body 16 forming a one piece handle 15.

The reamer 22 is removably connected with the truncated conical head 21, of handle 15, by a close friction tight fit. The reamer 22 has the general contour of an ellipsoid, the end portions 25 and 26 of which are truncated, the major rear end of the body being indicated by numeral 25 and the minor end by the numeral 26. The reamer 22 is of hollow form, having a tapered or truncated conical socket 24 therein, the outlet of said socket 24 being adjacent the rear end 25 thereof. The base of the socket has a short cylindrical chamber 27 therein. An axial channel 28 extends from the flat end surface 29 of the reamer and communicates with said chamber 27 to provide an air passage therebetween and air in the chamber at atmospheric pressure. The smaller end of the conical head 21 extends into the chamber 27 as surface wear develops between head 21 and socket 24 during use thereof. The reamer 22 is provided with coarse helical tooth cutters 30 formed on the curved longitudinal surface by the helical grooves 32 arranged therein.

The pipe 35 shown in FIGURE 1 consists of a pipe bowl 36, shank 37, the shank having a bore 38 communicating with the bowl. The stem 39 may be made of hard rubber, or other material; the bite 40 is flattened in the usual manner. The stem 39 has a cylindrical tenon 41 which has a close sliding fit with bore 38 of shank 37. A metal tube 42 is assembled in the longitudinal bore 43 in the stem 39, the outer free end of the tube 42 extending into bore 38. The stem 39 is removably fitted into the bore 38 of shank 37, the stem being easily removed to be cleaned and allowing easy access to clean bore 38. In general the maximum outside diameter of the reamer is somewhat less than the diameter of the opening 45 of the pipe bowl 36; this becomes important to the reaming operation of the baked ash 44 which forms in the bowl 36. The cutters 30 formed by a series of alternating grooves 32 define sharp edges which scrape the cake 44 from the inside of the pipe bowl when the handle 15 is grasped by the user, the reamer inserted into the bowl and rotated with a reaming action against the internal surface of the bowl. The reamer is so formed that it can be inserted substantially all the way into the bottom of the bowl. Various size reamers may be placed upon the conical head 21 of handle 15; the reamer 22 can be pried off by inserting a tool, or coin, between the end 25 of the reamer and disc 19 of the handle 15.

Referring to FIGURES 7-10, a liquid absorbing tool is shown, which has been identified broadly by numeral 50, which consists of a handle 51 with rounded free rear end 52, the handle 51 having a truncated conical socket 53 in the opposite end thereof. A liquid absorbing head member 54, formed of rubber or the like, has a configuration similar to a segment of paraboloid of revolution; or an ellipsoid, with small flat end 55, and a flat

rear end 56 with substantially truncated conical head, or tenon 58. The said tenon 58 being of such a size as to have a close sliding fit with socket 53 when assembled therewith. The tenon 58 is provided with longitudinal slots or grooves 59 to receive longitudinal key members 60 formed on side walls of socket 53. The rubber head 54 can be inserted into the bowl and rotated by the user grasping handle 50 and rotating it with a wiping action against the interior pipe bowl surfaces.

Referring to FIGURE 11, a stem-bore cleaner 70 is shown having cylindrical wood head portion 71 and a long working portion 72 formed of a wire containing absorbent material 73 exposed throughout its length, made in a way which is known in the art.

Referring to FIGURE 12, a pipe shank bore cleaner 77 is shown with head portion 75 and working portion 76, said portion 76 being relatively short, made of wire covered with absorbent material 78. By removing stem 39 from bore 38 of shank 37, it is easy to operate the bore cleaner 77 within bore 38.

Having thus described the several useful and novel features of the pipe cleaner set of tools of the present invention, it will be seen that the many worthwhile objects for which it was designed have been achieved. While only a few specific embodiments of the invention have been illustrated in the accompanying drawings, we realize that certain changes and modifications therein may well occur to those skilled in the art within the broad teaching thereof; hence, it is my intention that the scope of protection afforded hereby shall be limited only insofar as said limitations are expressly set forth in the appended claim.

I claim:

A two piece smoke pipe cleaner assembled axially in a common plane comprising, an elongated wooden handle and a reamer removably secured together by a close friction tight fit, said handle having a concave elongated handle gripping portion adapted to be grasped by the user, said handle having a rounded free rear end portion at one end of said gripping portion thereof, said handle having a disc portion at the opposite end of said hand gripping portion having an outer free side, said disc portion being of a diameter substantially the same as the largest transverse diameter of the handle, a step-portion of smaller diameter than said disc portion integral with the free side of said disc portion, and a tenon carried by and spaced axially from the hand gripping

portion of said handle by said step-portion and said disc portion, said tenon being a truncated conical head member integrally formed with said step-portion, said disc portion and said hand gripping portion of said handle, and with its smaller end portion extending axially in a direction away from said step-portion, said reamer having a body of substantially ellipsoidal form with a convex surface, a flat exterior front wall and a flat exterior rear end wall, whereby the front end portion of said body may be inserted downwardly into the bowl of a pipe, the front end portion of said body being smaller than the rear end portion thereof, the rear end portion of said body being hollow and the interior walls providing a truncated conical socket of approximately the same shape as that of said truncated conical tenon and having an interior flat base wall and conical side wall, the interior side wall of said body adapted to receive said truncated conical tenon in a tight frictional fit when assembled together and spaced a short distance from the interior flat base wall, the forward and portion of said reamer body being substantially solid, and said reamer body formed with a series of external elongated grooves in its convex surface providing a plurality of helical convex rigid cutters adapted to cut foreign matter from the bowl of a pipe when inserted and turned therein.
